UNITED STATES PATENT OFFICE.

GEORGE W. RATHSAM, OF INDIANAPOLIS, INDIANA.

MACHINE FOR MAKING FLOWER-POTS.

SPECIFICATION forming part of Letters Patent No. 244,304, dated July 12, 1881.

Application filed May 3, 1881. (No model.)

To all whom it may concern:

Be it known that I, GEORGE WILLIAM RATHSAM, a citizen of the United States, residing at Indianapolis, in the county of Marion and State of Indiana, have invented certain new and useful Improvements in Machines for Making Flower-Pots; and I do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

15 My invention relates to certain new and useful improvements in machines for the manufacture of flower-pots, and more especially to the class employing a revolving core-mold or male former, and a matrix or female former 20 having a vertically-adjustable bottom, the said core-mold and matrix being adapted to be brought together so as to form pottery articles within the space existing between the outer and inner surfaces of the said core-mold and 25 matrix, and the newly-formed article lifted out of the matrix by said adjustable bottom; and my invention has for its object the production 30 of a machine in which the matrix and adjustable bottom can be independently regulated or adjusted for the manufacture of different-sized pots; and the invention consists in novel features of construction, and combination and arrangement of parts, all as will be herein fully described, and specifically pointed out in the 35 claims.

Referring to the accompanying drawings, Figure 1 represents a side view of my improved machine; Fig. 2, a front view of the same; Fig. 3, a longitudinal section.

40 Similar letters of reference indicate like parts in all the views.

In the drawings, A represents the base, and B the four uprights of the frame of the machine.

45 C represents a frame adapted to be vertically adjusted, or moving in the slots b b of the front uprights, B B, through the medium of the hand-lever D, fulcrumed in the upright D', and connected to the V-shaped lower end of said 50 frame C by a cross-pin, d, working in slot d' in the front end of said hand-lever. The upper

cross-piece, e, of the frame C is centrally provided with a ring, e', in which rests the exterior mold or matrix, E, secured therein by a set-screw, e.

55 F represents the interior core or former, adjustably secured on the lower end of the shaft G by a set-screw, f, said shaft working in bearings g g, and carrying at its upper end bevel-wheel H, which meshes with a similar wheel, 60 H', mounted on one end of a horizontal shaft, h, journaled in bearings h' h' on top of the frame of the machine, and carrying on its outer end a driving-belt wheel or pulley, I, through the medium of which wheels and pulley H, H', 65 and I a revolving movement is communicated to said interior core or former, F.

J represents a cross-bar, provided with slotted uprights jj, connected to the front uprights, B B, by set-screws i i, and with said cross-bar 70 J projecting pins or studs k, secured to the front sides of the side guides of the frame C, engage for limiting the downward movement of said frame. The bottom of said exterior mold or matrix, E, is a circular plate or disk, L, 75 having a punch, l, on its upper surface, and a downwardly-projecting rod, l', connected to its under side, which passes through a guide, m, and is provided with a screw-nut or stop, m', adjustable thereon, for limiting the downward 80 movement of said plate or disk, in order to suit the proper height desired of pot to be lifted out of the matrix E.

85 The operation of my improved machine is as follows: Motion is communicated to the interior mold or core by the belt-wheel and gear-wheels, as above described. The interior plate or disk, L, is then adjusted to suit the desired height of pot to be made, after which a sufficient mass of clay or other material dipped in 90 coal or other oil is placed in the matrix E. Then by pressing down on the hand-lever D the frame carrying the matrix is raised, so that it will inclose the revolving core or mold, which completes the operation of forming the pot, 95 any surplus material being forced out over the edge of the exterior mold or matrix. The hand-lever being now raised, the frame and matrix will be lowered, leaving the formed pot on the bottom plate or disk, L, or the pot adheres to 100 the revolving mold and is taken off, the studs k on the frame C engaging the bar J at the proper

time to prevent a too far downward movement of the matrix, and the bar J, being vertically adjustable, permits the matrix being limited in its movement in accordance to the size of 5 pot required.

Having thus fully described my invention, what I claim as new, and desire to secure by Letters Patent, is—

1. The vertically adjustable and sliding frame C, carrying the exterior core or matrix, and provided with the stops k k, in combination with the transverse adjustable bar J, substantially as and for the purpose herein shown and described.
- 15 2. The combination, with the exterior core or matrix, E, of the adjustable bottom plate or disk, L, having a punch, l, on its upper surface, and a downwardly-projecting rod connected to its under side, and having an adjustable screw-nut or stop, m', and the guide m, through which said rod passes, substantially as and for the purpose specified.

3. In a machine for forming flower-pots, the combination, with an interior revolving former, of a vertically-movable frame operated through 25 a hand-lever connected thereto, as shown, and provided with the exterior mold or matrix, E, the stops k, and guide m, the adjustable bottom plate, L, provided with a punch, l, and the vertically-adjustable transverse bar J, the several parts constructed and relatively arranged to operate substantially as specified.

4. The combination, with the vertically-movable frame C, having the stops k k, of the transverse stopping-bar J, provided with slotted 35 uprights, and connected to the uprights B B by set-screws i i, substantially as herein shown and described.

In testimony whereof I affix my signature in presence of two witnesses.

GEORGE WILLIAM RATHSAM.
